BY

Johnston Mealey
HIS ATTYS.

UNITED STATES PATENT OFFICE.

JOHNSTON MEALEY, OF HOWARD LAKE, MINNESOTA, ASSIGNOR OF ONE-HALF TO JOHN F. McDONALD, OF MINNEAPOLIS, MINNESOTA.

TRACE-FASTENING.

SPECIFICATION forming part of Letters Patent No. 621,838, dated March 28, 1899.

Application filed May 17, 1898. Serial No. 680,917. (No model.)

To all whom it may concern:

Be it known that I, JOHNSTON MEALEY, of Howard Lake, Wright county, State of Minnesota, have invented certain new and useful 5 Improvements in Tug or Trace Fastenings, of which the following is a specification.

This invention relates to means for fastening harness tugs or traces upon whiffletrees.

The object of the invention is to provide 10 means for securely attaching the tug to the whiffletree, and, further, to provide a tug-fastening upon the whiffletree which will tend to lift or level the whiffletree, and, further, to provide a device which will hold the slack 15 end of a tug.

The invention consists generally in the combination, with the whiffletree, of a thimble thereon provided with a downwardly-extending headed hook whereon the whiffletree is 20 arranged and also provided with a downwardly-bent hook to engage the upper edge of a tug, and thereby prevent the tug from slipping from said hook when the tug is slackened.

25 The invention further consists in the combination, with the foregoing, of an additional hook or fastening upon the inner end of said thimble to carry the slack end of a tug, all as hereinafter described, and particularly 30 pointed out in the claims.

The invention will be more readily understood by reference to the accompanying drawings, forming part of this specification, and in which—

35 Figure 1 is an end view of a tug-fastener or whiffletree-end finish embodying my invention. Fig. 2 is a plan view of the same. Figs. 3 and 4 are respectively end and plan views of the device adapted for sword-end 40 whiffletrees. Figs. 5 and 6 illustrate the form of the device when used upon whiffletrees having polygonal ends. Fig. 7 is a perspective view showing the tug in place upon the end of the whiffletree.

45 As shown in the drawings, the thimble or sleeve 2 is made to conform to the shape of the end of the whiffletree 3, whether it be round, oblong, or polygonal in cross-section. On the end of the thimble is the downwardly 50 curved or bent hook 4, the upright portion of which lies close to the end of the thimble

or sleeve, only sufficient room being allowed between the two parts to admit the thickness of the tug or trace 5. The tug or trace is secured upon the forwardly-extending hook 55 or finger 6, projecting from the forward side of the thimble and having a T-head 7 to retain the tug after it is slipped over the same. Upon the inner end and rear side of the thimble is a hook or finger 8, which is adapted 60 to hold the end of the tug, as shown in Fig. 7. The hook 8 is preferably raised above the lower side of the thimble, so that the end of the tug is lifted and thus held up firmly in the hook 4. The T-head 7 and the hook 4 65 effectually hold the trace or tug against the end of the whiffletree, and the pull of the trace is directed upon the whiffletree at a point forward of the front side thereof and forward of the pivot of the whiffletree, so that 70 the tendency is to tilt or turn the whiffletree back, and thus level it and overcome the strain that tends to tilt it forward upon its pivot-bearing.

All parts of the device are preferably integral; but the small hook 8 may, if desired, be 75 separate and be in the form of a hook, bolt, or screw that may pass through the thimble and through the whiffletree, and thus serve to secure the sleeve or thimble 2 upon the 80 whiffletree, other fastenings being dispensed with, as indicated in Fig. 6.

Having thus described my invention, I claim as new and desire to secure by Letters Patent—

1. The fastening herein described, comprising the thimble or sleeve 2, the downwardly bent or turned hook 4 on the end thereof, and the hook or finger 6 projecting from the forward side of said sleeve or thimble and provided with a retaining-head. 85

2. The herein-described trace or tug fastening, comprising the thimble or sleeve 2, the downwardly-extending hook or finger 4 on the end thereof, and the forwardly-extending and outwardly-turned hook or finger 6, provided with a T-head 7, substantially in line with the outer part of the said hook 4, substantially as described. 90

3. The combination, with a whiffletree having straight ends, of thimbles arranged upon said ends, hooks or fingers 6 projecting from 95

the forward sides of said thimbles and having outwardly-curved ends provided with heads 7 to retain the tugs upon said ends, downwardly-curved hooks 4 provided on the outer ends of said thimbles, said heads being substantially in line with the outer parts of said curved hooks, the spaces between the upright portions of said hooks 4 and the ends of said thimbles corresponding substantially to the thickness of a tug whereby the same will be firmly held against the ends of the whiffle-tree, substantially as described.

4. The combination, with a whiffle-tree, of a sleeve or thimble 2 provided on the end thereof, a hook or finger 6 projecting from the forward side of said hook or thimble and having an outwardly-curved end provided with a head 7 to retain the tug in position on

said hook, a downwardly-curved hook 4 provided on said thimble, the end of said hook 6 being in advance of the pivotal point of said whiffle-tree and substantially in line with said hook 4, a space being formed between the upright portion of said hook 4 and the end of said thimble corresponding substantially to the thickness of a tug, and an upwardly-curved hook 8 provided on the rear side of said thimble and at or near its inner end, substantially as described.

In testimony whereof I have hereunto set my hand, this 20th day of April, 1898, at Minneapolis, Minnesota.

JOHNSTON MEALEY.

In presence of—

C. G. HAWLEY,
M. E. GOOLEY.
